UNITED STATES PATENT OFFICE.

EMILIO ALBERTI, OF NEW YORK, N. Y., ASSIGNOR TO INTERNATIONAL CORK COMPANY,
OF BROOKLYN, NEW YORK, A CORPORATION OF NEW YORK.

FEEDING ATTACHMENT FOR CROWN-CORK-MAKING MACHINES.

1,255,122.

Specification of Letters Patent.

Patented Feb. 5, 1918.

Application filed August 4, 1917. Serial No. 184,485.

To all whom it may concern:

Be it known that I, EMILIO ALBERTI, a citizen of the United States, and a resident of the city of New York, in the county of 5 Kings and State of New York, have invented certain new and useful Improvements in Feeding Attachments for Crown-Cork-Making Machines, of which the following is a specification.

10 The present invention relates to machines for manufacturing bottle-, can-, and like closures of the cap variety, including those termed "crown corks". The invention pertains more particularly to means for feeding 15 the sealing disks of cork or similar material of the closures to the assembling devices of the machine.

The main object of the invention is to provide a simple and efficient attachment 20 for cap making machines, which automatically delivers the sealing disks from a mass to the assembling machine without regard to the thickness, weight, and more or less curved shapes of the disks.

25 With these and other objects in view, which will more fully appear as the nature of the invention is better understood, the same consists in the combination, arrangement, and construction of parts hereinafter 30 described, pointed out in the appended claims and illustrated in the accompanying drawings, it being understood that many changes may be made in the size and proportion of the several parts and details of 35 construction within the scope of the appended claims without departing from the spirit or sacrificing any of the advantages of the invention.

One of the many possible embodiments of 40 the invention is illustrated in the accompanying drawings, in which:—

Figure 1 is a central vertical section taken through a feeding attachment constructed in accordance with the present invention; 45 Fig. 2 is a section taken on line 2—2 of Fig. 1, on a larger scale; Fig. 3 is a section taken on line 3—3 of Fig. 1, also on a larger scale; Fig. 4 is a section similar to Fig. 1, showing, on a larger scale, the top portion

of the apparatus; and Fig. 5 is a section 50 taken on line 5—5 of Fig. 4.

In the drawings, the numeral 10 indicates a portion of the frame of a crown cork assembling machine, having upon its table portion 11 mounted an upwardly extending support 12, which carries a hopper 13, that is in the case illustrated in the drawings of cylindrical shape, its lower portion 14 being conical to cause the disks therein to move toward its longitudinal center line. 60 The bottom 15 of this hopper is made of a separate piece, and is adapted, as will hereinafter appear, to be vibrated or oscillated. The bottom is slightly concave and provided, preferably, in its center line 65 with a circular outlet 16, the diameter of which is slightly larger than that of an individual sealing disk. Upon the underface of the bottom is formed a downwardly projecting tubular extension 17, through 70 which the disks are discharged from the hopper. This extension, which constitutes the outlet of the hopper, is seated eccentrically in a bushing 18, the latter being rotatably mounted in a step-bearing 19, that 75 is suitably attached to the support 12. To reduce undue friction between the bushing and the bearing, there are formed raceways 20 and 21 in the said bushing and bearing, respectively, and in these raceways run 80 balls 22 in the well-known manner. The bushing may be rotated in any suitable manner from the main driving shaft of the assembling machine, for instance there may be mounted upon the bushing a pulley 23, 85 over which runs a belt 24, that runs also over a pulley 25, the latter being mounted upon a rotating shaft 26 of the assembling machine. Sheaves 27 guide the movement 90 of said belt. In order to prevent the bottom 15 from rotating with the bushing, there is formed upon the underface of said bottom a lug 28, carrying an anti-friction roller 29, which is seated in a substantially radially extending recess 30, that is formed in an 95 extension 31 of the support 12.

The tubular outlet 17 of the hopper bottom is in alignment with the flaring mouth

32 of a stationary, preferably, vertically extending tube 33, leading to the transporting means 34 of the machine, which conveys the sealing disks one after the other to 5 the assembling mechanism. The tube 33 is held above the transporting mechanism by a standard 35, and is provided in its wall with longitudinal slots 36, permitting of the insertion of a pointed instrument for 10 the purpose of properly arranging the disks therein, should by accident some of the same travel therein edgewise.

In order to prevent the whole mass of 15 sealing disks from resting upon the hopper bottom and from clogging the outlet thereof, there is held a substantial distance above said bottom, within the hopper, an inverted substantially funnel-shaped member 37.

The hopper bottom is provided with 20 perforations 38, having each a diameter that is smaller than that of a sealing disk. As the hopper bottom is oscillated or vibrated, broken disks and foreign matter are sifted out from the mass. To prevent such broken 25 parts and foreign matter from falling upon the step-bearing, there is formed upon the tubular extension 17 a collar 39, covering the step-bearing.

Through the funnel-shaped member 37 30 extends preferably centrally a spindle 40, the upper end of which is screw-threaded, the said threads meshing with those of a wing-nut 41, which abuts against the upper face of the funnel-shaped member 37. To the 35 spindle 40 is attached in any suitable manner a disk 42, disposed a substantial distance above the circular outlet 16. To this disk are fixedly secured downwardly extending pins 43, which are disposed around the 40 outlet of the bottom, their lower ends reaching into perforations 38 in the said bottom. The position of the disk 42 and the pins 43 thereon may be adjusted in relation to the bottom by turning the wing-nut 41 in one 45 or the other direction.

Near the outlet of the tube 33 there is formed in the same a slot 44, in alignment with which is held upon the standard 35 a shiftable stop 45, adapted to be projected 50 into the said tube so as to prevent disks therein from falling onto the transporting means 34. This mechanism is made use of if the assembling device gets out of order and it becomes necessary to stop the feeding 55 of disks thereto.

The operation of this device is as follows: A mass of sealing disks is placed indiscriminately into the hopper and rotation imparted to the bushing 18. Inasmuch as the 60 tubular outlet of the hopper bottom is seated eccentrically in said bushing and a rotation of the hopper bottom is prevented as above described, the said bottom will be oscillated or vibrated, with the result that the disks

thereon, in traversing the outlet of the bottom, are caused to pass into the tubular extension thereof. As this tubular extension oscillates or vibrates above the flaring mouth of the tube 33, the disks will be discharged into the said tube. The continuous oscillation or vibration of the tubular extension 17 of the hopper bottom causes a proper stacking of the disks therein. No matter in what position they arrive in the tubular extension, they will be brought, by the continuous vibrating motion, before they reach the flaring mouth of the tube 33, into substantially horizontal position and into exactly horizontal position as they pass into the stationary tube 33. The thickness and more or less curved shapes of the disks does not affect the proper operation of the device. The stationary pins 43 around the circular outlet 16 of the bottom form, together with the disk 42, a cage which has a two-fold 65 purpose, to wit: First, it agitates the mass of disks on the bottom of the hopper as the said bottom is being vibrated, and, second, it prevents a clogging of the outlet of the hopper, in that it permits only a limited 70 number of disks from moving toward the said outlet at a time.

It is obvious that, while herein a specific means has been disclosed for vibrating or oscillating the hopper bottom, any other 95 means could be provided without departing from the invention, which lies mainly in providing a stationary cage within the hopper and around the outlet thereof for the 100 purpose set forth.

What I claim is:

1. In a device of the character described, the combination with a hopper having a tubular outlet, of a stationary tube leading from said outlet and provided with a mouth having a diameter larger than that of said outlet, means for vibrating said tubular outlet in relation to said tube, and a plurality of stationary pins within said hopper around 105 said outlet.

2. In a device of the character described, the combination with a hopper having a tubular outlet, of a stationary tube leading from said outlet and provided with a mouth having a diameter larger than that of said outlet, means for vibrating said tubular outlet in relation to said tube, and a stationary cage within said hopper disposed around 115 said outlet.

3. In a device of the character described, the combination with a hopper having a bottom provided with a tubular outlet, of a stationary tube leading from said outlet and provided with a mouth having a diameter larger than that of said outlet, means for vibrating said bottom and outlet in relation to said tube, and a plurality of stationary pins within said hopper around 120 said outlet.

4. In a device of the character described, the combination with a hopper having a bottom provided with a tubular outlet, of a stationary tube leading from said outlet and provided with a mouth having a diameter larger than that of said outlet, means for vibrating said bottom and outlet in relation to said tube, and a stationary cage within said hopper disposed around said outlet. 65
5. In a device of the character described, the combination with a hopper having a perforated bottom provided with a tubular outlet, of a stationary tube leading from said outlet and provided with a mouth having a diameter larger than that of said outlet, means for vibrating said bottom and outlet in relation to said tube, and a plurality of stationary pins within said hopper around said outlet, the lower ends of said pins reaching within perforations in said bottom. 70
- 10 6. In a device of the character described, the combination with a hopper having a tubular outlet, of means for vibrating said outlet, and a plurality of stationary pins within said hopper disposed around said outlet. 75
- 15 7. In a device of the character described, the combination with a hopper having a tubular outlet, of means for vibrating said outlet, and a stationary cage within said hopper disposed around said outlet. 80
- 20 8. In a device of the character described, the combination with a hopper having a bottom provided with a tubular outlet, of means for vibrating said bottom and outlet, and a plurality of stationary pins within said hopper disposed around said outlet. 85
- 25 9. In a device of the character described, the combination with a hopper having a bottom provided with a tubular outlet, of means for vibrating said bottom and outlet, and a stationary cage within said hopper disposed around said outlet. 90
- 30 10. In a device of the character described, the combination with a hopper having a perforated bottom provided with a tubular outlet, of means for vibrating said bottom and outlet, and a plurality of stationary pins within said hopper around said outlet, the lower ends of said pins reaching within perforations in said bottom. 100
- 35 11. In a device of the character described, the combination with a hopper having a perforated concaved bottom provided with a tubular outlet, of means for vibrating said bottom and outlet, and a plurality of stationary pins within said hopper around said outlet, the lower ends of said pins reaching within perforations in said bottom. 105
- 40 12. In a device of the character described, the combination with a hopper having a tubular outlet, of a stationary tube leading from said outlet and provided with a mouth having a diameter larger than that of said outlet, means for vibrating said bottom and outlet in relation to said tube, an inverted substantially funnel-shaped member disposed within said hopper a substantial distance above said outlet, and a plurality of pins depending from said funnel-shaped member and surrounding said outlet. 110
- 45 13. In a device of the character described, the combination with a hopper having a tubular outlet, of a stationary tube leading from said outlet and provided with a mouth having a diameter larger than that of said outlet, means for vibrating said bottom and outlet in relation to said tube, an inverted substantially funnel-shaped member disposed within said hopper a substantial distance above said outlet, and a cage depending from said funnel-shaped member and surrounding said outlet. 115
- 50 14. In a device of the character described, the combination with a hopper having a bottom provided with a tubular outlet, of a stationary tube leading from said outlet and provided with a mouth having a diameter larger than that of said outlet, means for vibrating said bottom and outlet in relation to said tube, an inverted substantially funnel-shaped member disposed within said hopper a substantial distance above said outlet, and a plurality of pins depending from said funnel-shaped member and surrounding said outlet. 120
- 55 15. In a device of the character described, the combination with a hopper having a bottom provided with a tubular outlet, of a stationary tube leading from said outlet and provided with a mouth having a diameter larger than that of said outlet, means for vibrating said bottom and outlet in relation to said tube, an inverted substantially funnel-shaped member disposed within said hopper a substantial distance above said outlet, and a cage depending from said funnel-shaped member and surrounding said outlet. 125
- 60 16. In a device of the character described, the combination with a hopper having a perforated bottom provided with a tubular outlet, of a stationary tube leading from said outlet and provided with a mouth having a diameter larger than that of said outlet, means for vibrating said bottom and outlet in relation to said tube, an inverted substantially funnel-shaped member disposed within said hopper a substantial distance above said outlet, and a plurality of pins depending from said funnel-shaped member and surrounding said outlet, the lower ends of said pins reaching within perforations in said bottom. 130
- 65 17. In a device of the character described, the combination with a hopper having a tubular outlet, of means for vibrating said outlet, an inverted substantially funnel-shaped member disposed within said hopper

1
a substantial distance above said outlet, and a plurality of pins depending from said funnel-shaped member and surrounding said outlet.

5 18. In a device of the character described, the combination with a hopper having a tubular outlet, of means for vibrating said outlet, an inverted substantially funnel-

shaped member disposed within said hopper a substantial distance above said outlet, and a cage depending from said funnel-shaped member and surrounding said outlet. 10

Signed at New York, in the county of Kings and State of New York, this 17th day of July, A. D. 1917.

EMILIO ALBERTI.
